CURTAIN OPERATING MECHANISM

Walter J. Stuber, Philadelphia, Pa., assignor to
Carey-McFall Company, Philadelphia, Pa., a
corporation of Pennsylvania

Application April 19, 1932. Serial No. 606,168

14 Claims. (Cl. 156—28)

This invention relates to operating means for curtains and has for its primary object to provide means whereby the driver of a motor driven vehicle may readily operate a rear curtain without 5 interference with the driving of the car.

Another object of the invention is to provide means of the character set forth having novel means whereby the curtain may be readily and conveniently adjusted into closed position and 10 effectively maintained in such position, said means also permitting a ready release to allow the curtain to return to its normal open position.

Another object of the invention is to provide 15 a curtain operating mechanism of the character set forth having novel construction whereby the curtain may be readily and conveniently positioned to effect a partial or entire closure of the rear window and be effectively maintained in such position.

20 The invention contemplates certain other novel features and details of the construction of the particular mechanisms for adjusting the curtain into position and effecting the ready release to allow the curtain to return to its normal open position.

These features and details of construction are set forth hereinafter and shown in the accompanying drawings, in which:

25 Figure 1 is a diagrammatic view showing the 30 device constituting the invention and its relation with respect to a vehicle;

Fig. 2 is a front elevation view of the rear curtain roller mechanism and the supports therefor;

Fig. 3 is a view on line 3—3, Fig. 2;

35 Fig. 4 is a view in section on line 4—4, Fig. 2;

Fig. 5 is a view in section on line 5—5, Fig. 4;

Fig. 6 is a view in section on line 6—6, Fig. 7; and

Fig. 7 is a view in section on line 7—7, Fig. 6.

40 Referring now more particularly to the drawings, 1 denotes a curtain of conventional type associated with a spring actuated roller 2 which operates to maintain the said curtain 1 wound therearound and in open position with respect to the rear window 3 of the automobile or similar vehicle body.

The spring roller 2 is supported adjacent the rear window 3 of the vehicle by the brackets 4 and 5 respectively and arranged for rotation with 45 respect thereto. The previously mentioned bracket 4 comprises a stationary casing 6 having a rivet or pin 7 secured therein and extending outwardly therefrom. A drum 8 is rotatably mounted on the pin or rivet 7 internally of casing 6. The curtain roller 2 is connected to the

drum 8 through the end cap 9 of the roller which embraces the rivet 7 and is provided with the projecting tongues 9a arranged to engage the slots 8a formed in the adjacent face of the drum 8.

The casing 6 is provided with an opening 6a in the circumferential surface thereof to permit entrance internally of said casing of a cord or other pull means 10, the said cord being wound about the drum 8 and having the adjacent end 60 thereof connected to said drum, in such a manner that a pull on the cord 10 rotates the drum 8 and the curtain roller 2 to unwind the curtain therefrom. The cord 10 is continued through a forwardly directed conduit or tubular member 65 11, preferably positioned in the roof or top structure of the car body, the said conduit 11 having its forward end terminating at a point above the back or front of the driver's seat.

The cord 10 extends downwardly from said forward or front end of the conduit 11 outwardly through an aperture 12 in a fixed plate 12 and is attached to a drum 13 rotatably mounted on the spindle 14 projecting centrally from said plate 12. The outer end portion of the spindle 70 14 is of enlarged square or rectangular cross section 15 as shown in Fig. 6 of the drawings.

The drum 13 is provided with a radially disposed flange 16 on which a pawl 17 is pivotally mounted, the said pawl 17 acting against the 75 force of a spring 18 against a fixed stop 19. A ratchet element 20 is mounted upon the enlarged portion 15 of the spindle 14 and arranged for sliding movement thereon. A pyramidal coil spring 21 embraces the portion 15 of the spindle 80 14 and resides in the annular recess 22 formed in the outer face of the drum 13 intermediate the said drum and the ratchet. A cap 23 slidably embraces the extremity of the spindle 14 and has its inner edge in abutting relation with the outer 85 face of the ratchet 20, the said cap 23 being further provided with a shoulder 24 arranged to abut the inner edge of an annular opening 25 in a casing 26 through which the outer end of the cap 23 projects. The casing 26 is secured to the periphery of the drum flange 16 by means of screws 90 27 in a manner effecting rotation of the drum 13 when the said casing 26 is rotated.

The shoulder 24 on the cap 23 functions as an 95 abutment limiting the outward movement thereof and when the cap is in this outermost position and the shoulder 24 abuts the inner edge of the aperture 25 formed in the casing 26, the teeth of the ratchet 20 will be in engagement with the pawl 17 and be maintained in that position by 100 105 110

the force of the coil spring 21. The ratchet 20 and pawl 17 may be respectively disengaged by depressing the cap 23 inwardly on the spindle 14 against the action of the spring 21 and out of the 5 path of the pawl 17.

In the operation of the curtain mechanism set forth rotation of the casing 26 and drum 13 in a direction to wind the cord 10 about the drum 13, results in the unwinding of the other end of the 10 cord 10 from the drum 8, the said drum rotating and in turn rotating the roller 2 in a direction to unwind the curtain 1 therefrom. The pawl 17 and the drum 13 rotate about the teeth of the ratchet 20, the said pawl 17 successively engaging 15 the circumferentially disposed teeth of the ratchet 20 permitting rotation in a forward direction only and preventing the rewinding of the curtain 1 upon the roller 2. By the novel pawl and ratchet arrangement set forth above, the curtain 1 may be entirely or partially unwound from the roller 2 and effectively maintained in that 20 position. This particular feature of the invention permits the operator of the vehicle to effect a complete or partial closure of the rear window 25 3 of the vehicle, as may be desired, the pawl 17 engaging the ratchet 20 to maintain the curtain in that position with respect to the said window of the vehicle.

When it is desired to rewind the curtain upon 30 the roller 2, the depression of the cap 23 inwardly of the casing 26 against the action of the spring 21, moves the ratchet 20 out of the path of the pawl 17, permitting the spring internally of the curtain roller 2, to rewind the curtain upon said roller, the pull cord 10 being simultaneously wound about the drum 8 and unwound from the drum 13. When the curtain 1 is entirely rewound upon the roller 2, the cap 23 may be released and the spring 21 will move the ratchet 20 outwardly 35 on the spindle 14 placing the teeth thereof into engagement with the pawl 17 ready for any subsequent entire, or partial closure of the rear window 3 by the curtain 1.

From the foregoing description it is believed to 40 be obvious that an operating means for vehicle curtains constructed in accordance therewith, is particularly well adapted for use in the manner intended by reason of the convenience of its operation, and it will also be obvious that the invention herein set forth may be susceptible to some change without departing from the spirit thereof except as hereinafter claimed.

What is claimed is:

1. The combination of a spring roller, a curtain 45 normally maintained in a wound state on said roller by rotation of the roller in one direction through the medium of the roller spring, a circumferentially grooved drum at and operatively attached to one end of the roller beyond a side 50 edge of the curtain, a pull cord wound on the drum within the groove thereof with one end of the cord secured to the drum, a casing closely surrounding the periphery of the drum to maintain the wound portion of the cord within said 55 groove, and a control element remotely situated with respect to the casing and to which the opposite end of said cord is secured.

2. The combination with a spring roller having 60 one end of a curtain and one end of a pull cord secured to and normally wound on the roller by rotation thereof in one direction through the medium of the roller spring, of a remote control for said curtain comprising a rotatable drum to which the opposite end of the pull cord is secured for unwinding the first said end of the cord

and the curtain from said roller in opposition to said spring, and means for maintaining the drum in any one of a plurality of positions to which it may be rotated, for maintaining the curtain in a corresponding unwound state relative to the 80 roller.

3. The combination with a spring roller mounted curtain, of a drum mounted for rotation and connected directly to said roller, a remote control element, a pull cord having one end attached to said drum and the other end to said remote control element, the rotation of said element acting through the pull cord to rotate the drum and roller and unwind the curtain therefrom, means preventing rotation of the remote control element in one direction, and means releasing said preventing means to permit free rotation of the remote control element in the opposite direction. 90

4. The combination with a spring roller mounted curtain, of a pin extending into one end of said roller, a drum rotatably mounted on said pin and having slots in the face thereof adjacent said end of the roller, a closure for said end of said roller, and tongues projecting outwardly from said closure and engaging the slots in the 100 drum to effect direct connection intermediate said roller and said drum.

5. The combination with a spring roller mounted for rotation about a horizontal axis and having one end of a curtain and one end of a pull cord 105 secured to and normally wound on the roller by rotation thereof in one direction through the medium of the roller spring with the opposite end of the curtain free to drop by gravity, of a remote control for said curtain comprising a rotatable drum to which the opposite end of the pull cord is secured for unwinding the first said end of the cord and the curtain from said roller in opposition to said spring, and means for maintaining the drum in any one of a plurality of positions to which it may be rotated, for maintaining the curtain in a corresponding unwound state 110 relative to the roller.

6. The combination with a spring roller mounted curtain of a pin projecting into one end of 115 said roller, a drum rotatably mounted on said pin and having slots in the face thereof adjacent said end of the roller, a closure for the said end of the roller, tongues projecting outwardly from said closure and engaging the slots in the drum 120 and effecting direct connection between said roller and said drum, a remote control element, and a pull cord having one end attached to said drum and the other end to said remote control element, the rotation of said remote control element acting through the pull cord to rotate the drum and 125 roller and unwind the curtain therefrom.

7. The combination with a spring roller mounted curtain of a pin projecting into one end of 130 said roller, a drum rotatably mounted on said pin and having slots in the face thereof, adjacent the said end of said roller, a closure for the said end of the roller, tongues projecting outwardly from said closure and engaging the slots in the drum 135 effecting direct connection intermediate said roller and said drum, a remote control element, a pull cord having one end attached to said drum and the other end to said remote control element, the rotation of said remote control element acting through the pull cord to rotate the drum and 140 roller and unwind the curtain therefrom, and means preventing rotation of the remote control unit in one direction.

8. The combination with a spring roller mounted curtain having a pull cord attached thereto, 145

- of a remote control element comprising rotatable means to receive said pull cord, means normally preventing rotation of the first named means in one direction, and means controllable at will, releasing said preventing means to permit rotation of said means in the opposite direction. 9. The combination with a spring roller mounted curtain having a pull cord attached thereto, of a remote control element comprising a rotatable drum having the pull cord attached thereto, means normally preventing rotation of the drum in one direction and maintaining the drum in the position to which it is rotated, and means controllable at will releasing said preventing means to permit rotation of the drum in the opposite direction. 10. The combination with a spring roller mounted curtain having a pull cord attached thereto, of a remote control element comprising a spindle, a drum rotatably mounted on said spindle to receive said pull cord, a pawl mounted on the drum, a ratchet slideable on said spindle and cooperating with said pawl to prevent rotation of the drum in one direction, and means effecting disengagement of the ratchet and pawl to permit free rotation of the drum on the spindle. 11. The combination with a spring roller mounted curtain, having a pull cord attached thereto, of a remote control element comprising a spindle, a drum rotatably mounted on said spindle, a pawl mounted on said drum, a ratchet slideable on the spindle for engagement by said pawl, preventing rotation of the drum in one direction, a casing having an aperture therein rotatably mounted with respect to said ratchet and connected to said drum, a spring embracing the spindle normally maintaining the ratchet in position for engagement by the pawl, and a cap de-pressible against said spring and abutting said ratchet for disengaging the ratchet and the pawl to permit free rotation of the drum about said spindle. 12. The combination with a spring roller mounted curtain having a pull cord attached thereto, of a remote control element comprising a spindle, a drum rotatably mounted on said spindle to receive said pull cord, a pawl mounted on the drum, a ratchet slideable on said spindle and cooperating with said pawl to prevent rotation of the drum in one direction, and means effecting disengagement of the ratchet and pawl to permit free rotation of the drum on the spindle. 13. The combination with a spring roller mounted curtain, having a pull cord attached thereto, of a remote control element comprising a spindle, a drum rotatably mounted on said spindle, a pawl mounted on said drum, a ratchet slideable on the spindle for engagement by said pawl preventing rotation of the drum in one direction, a casing having an aperture therein rotatably mounted with respect to said ratchet and connected to said drum, a spring embracing the spindle normally maintaining the ratchet in position for engagement by the pawl, and a cap de-pressible against said spring and abutting said ratchet for disengaging the ratchet and the pawl to permit free rotation of the drum about said spindle. 14. The combination with a spring roller mounted curtain having a pull cord attached thereto, of a remote control element comprising a spindle, a drum rotatably mounted on said spindle, a pawl mounted on said drum, a ratchet slideable on the spindle for engagement by said pawl preventing rotation of the drum in one direction, and maintain the drum in the position to which it is rotated, a casing having an aperture therein rotatably mounted with respect to said ratchet and connected to said drum, a spring embracing the spindle normally maintaining the ratchet in position for engagement by the pawl, and a cap de-pressible against said spring and abutting said ratchet for disengaging the ratchet and the pawl to permit free rotation of the drum about said spindle. 15. 16. 17. 18. 19. 20. 21. 22. 23. 24. 25. 26. 27. 28. 29. 30. 31. 32. 33. 34. 35. 36. 37. 38. 39. 40. 41. 42. 43. 44. 45. 46. 47. 48. 49. 50. 51. 52. 53. 54. 55. 56. 57. 58. 59. 60. 61. 62. 63. 64. 65. 66. 67. 68. 69. 70. 71. 72. 73. 74. 75. 76. 77. 78. 79. 80. 81. 82. 83. 84. 85. 86. 87. 88. 89. 90. 91. 92. 93. 94. 95. 96. 97. 98. 99. 100. 101. 102. 103. 104. 105. 106. 107. 108. 109. 110. 111. 112. 113. 114. 115. 116. 117. 118. 119. 120. 121. 122. 123. 124. 125. 126. 127. 128. 129. 130. 131. 132. 133. 134. 135. 136. 137. 138. 139. 140. 141. 142. 143. 144. 145. 146. 147. 148. 149. 150.
